UNITED STATES PATENT OFFICE.

JOHN E. CONZELMAN, OF ST. LOUIS, MISSOURI, ASSIGNOR, BY MESNE ASSIGNMENTS,
TO UNIT CONSTRUCTION COMPANY, A CORPORATION OF DELAWARE.

CONCRETE CONSTRUCTION.

961,210.

Specification of Letters Patent. Patented June 14, 1910.

Original application filed January 9, 1909, Serial No. 471,431. Divided and this application filed April 29, 1909. Serial No. 492,860.

To all whom it may concern:

Be it known that I, JOHN E. CONZELMAN, a citizen of the United States, residing at the city of St. Louis, State of Missouri, have 5 invented certain new and useful Improvements in Concrete Construction, of which the following is a specification, reference being had therein to the accompanying drawings.

10 This invention relates to concrete building structures and has particular reference to a construction in which concrete slabs are used for ceilings and floors, and are supported at their corners or intermediate edges by 15 uprights or columns.

In the construction of concrete buildings, it is essential that proper unions be effected between the columns or uprights and the horizontal members or floor and ceiling slabs.

20 It is the object of this invention to provide a structure of concrete building elements which coöperate and are interengaged to form a rigid, secure and lasting jointure of said elements.

25 It is also an object to provide a concrete building structure in which the general construction of the coöperating upright and horizontal elements is generally improved to present a neat appearance as well as to 30 prove of strong and durable nature.

This application is a divisional application of my copending application Serial Number 471,431, filed Jan. 9, 1909.

In the accompanying drawings, which 35 form part of this specification and in which like numerals denote similar parts throughout, Figure 1 is a vertical sectional view of my improved construction, and Fig. 2 is a top plan thereof.

40 Referring more particularly to said drawings, 5 represents a column or upright rising from the foundation or lower floor (not shown) of a building structure, and having resting on its upper end a similar 45 column 2. The upper portion of said column 5 is enlarged to form a surrounding cap 4 and shoulder 8, thereby providing a stud 3.

50 6 are slabs of concrete forming the floor member or ceiling members as the case may be, and comprise molded panels having the reinforcing rods 9 sunk in the body thereof and lying below the top and bottom surfaces

thereof. A depending flange 7 is formed around the edges of the slabs, said flange 7 being adapted to rest upon the shoulder 8 formed by the cap 4. When the flanges 7 are thus located upon the shoulder 8, the upper part of the slabs 6 extends above said stud 3 to form a recess, said recess providing a seat or socket to receive the lower portion 1 of the superposed column 2. The reinforcing bars 9 are embedded in the upper part of slab 6 and elsewhere, but particularly extend, at least in part, above the line 65 where said stud 3 meets the lower portion 1 of column 2.

Having thus described my invention, what I claim and desire to secure by Letters Patent of the United States is:—

1. A concrete construction comprising, in combination, a column having an enlarged portion formed below its top to provide a surrounding cap and shoulder, an upwardly projected stud, a column conforming to said stud and superposed thereabove, slabs having the corners resting on said shoulder and abutting said stud and being spaced apart to provide spaces which radiate from said columns, and beams molded in said spaces. 80

2. A concrete construction, comprising, in combination, a column having an enlarged portion formed below its top to provide a surrounding cap and shoulder, an upwardly projected stud, a column conforming to said stud and superposed thereabove, slabs having corners supported on said shoulder and having their sides spaced apart in parallel relation to form spaces radiating from said columns, and beams molded in said spaces 90 to rest with an end on said shoulder.

3. A concrete construction, comprising, in combination, a column having an enlarged portion formed below its top to provide a surrounding cap and shoulder, an upwardly projected stud, a column conforming to said stud and superposed thereabove, rectangular slabs each having a corner resting on said shoulder, and being spaced from one another to form recesses between their sides, 100 and beams molded in said recesses to form a monolithic structure with said slabs and to have an end resting on said shoulder.

4. A concrete construction, comprising, in combination, a column having an enlarged portion formed below its top to provide a

surrounding cap and shoulder, an upwardly projected stud, a column conforming to said stud and superposed thereabove, rectangular slabs each having a corner resting on said 5 shoulder and projecting above said stud to surround said superposed column, said slabs being spaced apart to form recesses having parallel sides and radiating from said col-

umns, and beams molded between said slabs in said recesses.

10

In testimony whereof I have affixed my signature in presence of two witnesses.

JOHN E. CONZELMAN.
